UNITED STATES PATENT OFFICE.

HEYWARD A. PAXTON, OF DE LAND, FLORIDA.

METALLIC FENCE-POST AND WIRE-FENCE-FASTENING MEANS.

1,153,403.

Specification of Letters Patent. Patented Sept. 14, 1915.

Application filed January 16, 1915. Serial No. 2,649.

To all whom it may concern:

Be it known that I, HEYWARD A. PAXTON, a citizen of the United States, residing at De Land, in the county of Volusia and State of Florida, have invented a new and useful 5 Metallic Fence-Post and Wire-Fence-Fastening Means; and I do hereby declare the following to be a full, clear, and exact description of the invention, such as will enable others skilled in the art to which it 10 appertains to make and use the same.

This invention relates to a useful and improved metallic fence post and wire fence fastening means therefor, and as an object 15 of the invention it is the aim to provide a metallic fence post body having a socket on one face adjacent its lower end, to receive a contracted end of a clamping plate, between which and said body the fence wire is 20 clamped, there being lugs carried by the body, penetrating through the plate to receive wedges.

In practical fields the details of construction may necessitate alterations, falling 25 within the scope of what is claimed.

The invention comprises further features and combination of parts, as hereinafter set forth, shown in the drawings and claimed.

In the drawings: Figure 1 is a view showing the entire fence post and fastening means, illustrating the fence wire or wire mesh work as attached. Fig. 2 is a vertical sectional view showing parts broken and parts in elevation. Fig. 3 is a transverse sectional view on line 3—3 of Fig. 2. Fig. 4 is a view illustrating a portion of the fence post body, showing the socket, and the lower end of the plate in a position about to be received by the socket. Fig. 5 is a sectional view on line 5—5 of Fig. 1.

Referring more especially to the drawings, 1 designates the fence post body, which is substantially T-shaped in cross section. Adjacent the face 2 of the body near the lower 45 end thereof, a laterally projecting plate supporting member 3 is positioned, and fastened at 4 to the outer face of this member 3 is a metallic strap 5, which, as shown in one of the sectional views of the drawing, has its 50 ends overlying the opposite edge portions of the body of the post, which ends 6 are secured at 7 to the post, holding the supporting member securely in place. This supporting member 3 adjacent its upper surface 55 and adjacent the face in contact with the

face of the body is recessed forming a socket 8, to receive the lower contracted end 9 of the clamping plate 10. The clamping plate at its upper end and midway of its length is provided with rectangular openings 11, 60 through which the lugs 12 of the body of the post extend. These lugs are provided with vertical openings 13 to receive the wedges 14, thereby acting to clamp the plate adjacent the face 2 of the body of the post, thereby holding the wire fence securely. The inner face of the clamping plate is provided with a plurality of lugs 15, to prevent downward displacement of the horizontal wires 65 of the wire fence 16.

The invention having been set forth, what is claimed as new and useful is:

1. In combination, a metallic fence post body, a supporting block member having a recess adjacent one face and open upon said face and at the top, said block member being disposed next to one flat face of the post, thereby closing the side face of the recess forming a socket, a metallic strap arranged upon the outer face of said block member, 75 screws for securing the straps to the block member, said strap having its ends overlapping one face of the post opposite the face to which the block member is secured, screws penetrating the ends of the strap and into 80 the post and the block member thereby securing the strap and the block member to the post, a clamping plate having a contracted portion at its lower end received in said socket, and between which clamping plate 85 and the post the fence wire is clamped, and means for securing the clamping plate in place.

2. In combination, a fence post body T-shaped in cross section, a supporting member having a socket arranged adjacent one face of the body, a plate secured to said supporting member about its outer face and having its ends overlying the opposite edges of the body of the post and secured thereto, 95 thereby holding the supporting member in position, one face of the body of the post having laterally extending lugs, one adjacent the upper end of the body, another substantially midway of the length of the body, a clamping plate having a lower contracted end received in the socket and having a pair of openings corresponding in position with 100 relation to said lugs and designed to receive the lugs, said lugs having openings, wedges 105 110

passed through the openings of the lugs to hold the clamping plate in position, between which clamping plate and the body of the post the wire fence is arranged, and lugs 5 upon one face of the clamping plate to prevent downward movement of the horizontal wires of the wire fence.

In testimony whereof I have signed my name to this specification in the presence of two subscribing witnesses.

HEYWARD A. PAXTON.
